ATTORNEY

UNITED STATES PATENT OFFICE.

JOHN W. BULGER, OF EAST LIVERPOOL, OHIO.

DOOR-CHECK.

SPECIFICATION forming part of Letters Patent No. 290,526, dated December 18, 1883.

Application filed August 15, 1883. (No model.)

To all whom it may concern:

Be it known that I, JNO. W. BULGER, a citizen of the United States, residing at East Liverpool, county of Columbiana, and State 5 of Ohio, have invented certain new and useful Improvements in Door-Checks; and I do hereby declare the following to be a description of the same, and of the manner of constructing and using the invention, in such full, 10 clear, concise, and exact terms as to enable any person skilled in the art to which it app pertains to construct and use the same, reference being had to the accompanying drawings, which form a part of the specification, 15 the principle of the invention being herein explained, and the best mode in which I have contemplated applying that principle, so as to distinguish it from other inventions.

The object of this invention is to provide 20 an improved form of door-check adapted to maintain a door open at any desired point.

In the drawings, Figure 1 represents the door-check applied as in use. Fig. 2 is a perspective view of the door-check. Fig. 3 is a 25 central vertical longitudinal section of same.

The door-check consists of two parallel straight jaws, A, united at their front extremities by a joining portion, a. These jaws may be formed at any suitable distance apart, 30 corresponding to different thicknesses of doors. This door-check is made as an oblong integral device adapted to rest freely on the floor and to be slid thereon at will. The jaws and their joining portion have sliding bearing throughout

their entire area, and are formed heaviest and 35 broadest at their bottom. They are respectively made so that in vertical cross-section they are in the outline of a right-angle triangle. This permits their inner sides to be substantially vertical, while their outer sides 40 incline outwardly from the top to the bottom. The sides of the door can thus have continuous bearing against the inner vertical sides of the jaws throughout the latter's height and length; also, the door-check is formed of stable equilibrium, the broad base of it permitting it to 45 be moved freely in a sliding movement over the floor without liability to be tipped over.

This door-check may be made of any kind of metal, or of glass, rubber, porcelain, or 50 other material. It may be glazed, plated, or covered with cloth.

What I claim is—

The herein-described door-check, formed broad at the base and tapering toward the 55 top, the same consisting of the two straight jaws A and the joining portion a, said parts having vertical inner sides and outer sides which incline outwardly from the top to the bottom, substantially as set forth. 60

In testimony that I claim the foregoing to be my invention I have hereunto set my hand this 9th day of August, A. D. 1883.

JOHN W. BULGER.
